Primary Examiner — S. Bryan Reinholdt, Jr.*Assistant Examiner* — James T Tyree(74) *Attorney, Agent, or Firm* — Daryl R. Wright; Greg Carr(57) **CLAIM**

We claim the ornamental design for a model vehicle lighted roof skid assembly, as shown and described.

DESCRIPTION

FIG. 1 is an upper, left, front perspective view of a model vehicle lighted roof skid assembly showing our new design; FIG. 2 is a front elevation view thereof; FIG. 3 is a rear elevation view thereof; FIG. 4 is a right side elevation view thereof; FIG. 5 is a left side elevation view thereof; FIG. 6 is an upper plan view thereof; FIG. 7 is a lower plan view thereof; FIG. 8 is an upper, right, rear perspective view thereof; and, FIG. 9 is a lower, left, front view of the model vehicle lighted roof skid assembly.

In the drawings, the broken lines illustrate portions of the model vehicle lighted roof skid assembly that form no part of the claimed design.
